(57) **CLAIM**

The ornamental design for an iron golf club head, as shown and described.

DESCRIPTION

FIG. 1 is a bottom perspective view of an iron golf club head;

FIG. 2 is a front view thereof;

FIG. 3 is a top plan view thereof;

FIG. 4 is a rear view thereof;

FIG. 5 is a bottom plan view thereof;

FIG. 6 is a toe end view thereof; and,

FIG. 7 is a heel end view thereof.

The broken line showing of the groove lines on the striking surface is included for the purpose of illustrating and forms no part of the claimed design.
